UNITED STATES PATENT OFFICE.

ROBERT LIONEL WELCH, OF TORONTO, ONTARIO, CANADA.

WRAPPING-PAPER-PRINTING MACHINE.

1,131,757.

Specification of Letters Patent. Patented Mar. 16, 1915.

Application filed March 24, 1914. Serial No. 826,850.

To all whom it may concern:

Be it known that I, ROBERT LIONEL WELCH, of the city of Toronto, in the county of York, in the Province of Ontario, Canada, have invented certain new and useful Improvements in Wrapping-Paper-Printing Machines, of which the following is the specification.

My invention relates to improvements in 10 wrapping paper printing machines and the object of the invention is to devise a simple, compact machine for printing advertisements or other matter on either one of two rolls of wrapping paper, which may be of 15 different sizes and textures, in which the printing operation done on both rolls of paper is accomplished by one printing device so that either of the rolls of paper may be used so printed upon or plain, in which 20 both printing and paper roll supports may be easily gotten at for the purpose of either changing the printing roller or recharging the machine with new paper rolls, in which a simple paper feeder is provided whereby 25 the previously cut edge of the paper is easily fed forwardly from the edge of the cutting knife for the purpose of providing a grip for the withdrawal of paper off the roll, in which the cutting knives are so supported 30 and swung as to always remain in the same tangential position in relation to the periphery of the paper roll as the roll reduces from a maximum to a minimum diameter and it consists essentially of an open fronted casing 35 having an opening in the back wall thereof and guide-ways in the bottom thereof, a laterally withdrawable paper roll and printing mechanism, a supporting carriage located normally in the main casing and 40 capable of passing through the open front thereof, a plurality of paper roll supporting spindles removably mounted in the withdrawable frame, a platen roll also mounted in the withdrawable frame opposite each 45 paper roll support and over which the paper strips pass from the rolls, a printing roller, mechanism for alternately carrying the platen roller in and out of engagement with the printing roller, a cutting blade swing- 50 ably supported over each paper roll in contact with the periphery thereof, and automatic paper feeding device for feeding the cut edge of the paper forwardly of the cutting edge of the knife as hereinafter more 55 particularly explained by the following specification.

Figure 1, is a general perspective view of my device. Fig. 2, is a vertical section through Fig. 1 showing the normal position of the paper roll support in full lines and the withdrawn position in dotted lines. Fig. 3, is a perspective detail view of the printing roller and co-acting parts removed from the machine. Fig. 4, is a perspective detail of one of the cams for raising the printing roller. Fig. 5, is a detail of one of the paper feeding spools and operating mechanism thereof. Fig. 6, is a sectional detail view of the paper feeding spool operating lever.

In the drawings like letters of reference indicate corresponding parts in each figure.

A is the outer casing for containing my mechanism provided with an open front A' and an opening A² in the back wall A³ thereof.

A⁴ is a hinge door normally covering the opening A² and provided with a pivoted supporting leg A⁵ designed to assume by gravity the position shown in dotted lines 80 when the cover A⁴ is thrown down to the horizontal open position.

A⁶ are guiding grooves formed in the bottom A⁷ of the casing for a purpose which will hereinafter appear.

B is the paper roll and printing roller supporting frame comprising the side plates B' and B² connected together by an upper cross bar B³ and lower cross bars B⁴ and B⁵. Each side plate B and B' is provided at the 90 edge in proximity to the opening A² of the main casing with a bayonet slot B⁷, the opposite or forward edge of each plate being also provided with upper and lower bayonet slots B⁸ and B⁹.

C and C' are the paper roll supporting spindles, the ends of which are supported respectively in the bayonet slots B⁸ and B⁹. Each paper roll supporting spindle C and C' is provided with opposing tapered plugs C¹ and C² secured in position by set nuts C⁶.

C' are collars secured on each spindle C and C' in proximity to the end thereof and bearing when the spindle is in position within the bayonet slots B⁸ and B⁹ against the 105 inner faces of the side plates B' and B² thus preventing the longitudinal movement of the spindles C and C' within the bayonet slots.

D and D' are rolls of paper which may 110 vary both in width and texture, the plugs C⁴ and C⁵ fitting into the ends of the cen-

tral orifice extending through the paper rolls into which the plugs are forced by means of the set nut C^6 thereby centralizing the roller to the required position. In order to form a support for the center portion of the paper roll when it is unwound and approaching its minimum diameter I have provided the annular disks E and E' connected together by undulating resilient wires E^2 . When the paper roller has been placed in position upon the supporting spindle one of the plugs C^4 or C^5 is set to the required position. The spindle is then passed through the center of the paper roll and the washers E and E' connected by wires E^2 threaded on to the spindle against the inner end of the plug. It will, of course, be understood that in this position the undulations of the wires E^2 are spread so as to bring the wire nearer to a straight line than in the position shown in the drawing. The opposing plug is then threaded on to the spindle and forced up to the required position by the set nut C^6 , the undulations of the wires E^2 being thereby compressed together longitudinally of the wires and then shortened longitudinally but expanded radially so as to fill the space between the central spindle and the inner periphery of the wire thereby supporting the central portion of the roll.

F is a platen roller secured on the spindle F' journaled in a stationary position in the plates B' and B^2 and to the rear of the spindle C' .

B^{10} are arc-shaped slots formed in the plates B' and B^2 and in horizontal alinement.

F^2 is a spindle which extends between the plates B' and B^2 and at its ends through the slots B^{10} .

F^3 is a platen roller mounted upon the spindle F^2 to the rear of the spindle C hereinbefore described.

The paper strips D^2 and D^3 extend from the rolls D and D' beneath the platen rolls F and F^3 and pass over the same and return to the rolls D and D' over which they pass as shown particularly in Fig. 2 of the drawings.

G is a spindle extending between the plates B' and B^2 and through the slots B^7 .

H is a cam lever provided with an oval shaped cam H' and a retaining flange H^2 . In its normal position the cam H' fits within the bottom of the bayonet slot B^7 , the plate B' or B^2 fitting between the retaining flange H^2 and the body of the lever H . It will also be understood that each slot B^7 is provided with a cam H' , the ends of the spindle G resting upon the periphery of the cams in the position shown in the drawings.

I is a rod secured at its ends in the plates B' and B^2 .

J and J' are levers fulcrumed intermediate of their length upon the ends of the

rod I . The rear end of each lever J and J' is connected by a link J^2 to the end of the cam lever H . The opposite end of the lever J' is provided with an operating handle which extends in its normal position in a downwardly inclined direction past the front end of the plate B' .

J^3 is a supplemental lever provided at one end with a slotted enlargement J^4 . A lever J^3 is located to the outside of each plate B' and B^2 in proximity to the slots B^{10} so as to receive through its slotted end J^4 the projecting ends of the spindle J^2 .

J^5 are links connecting the opposite ends of the levers J^3 with the levers J and J' as shown by full lines in Fig. 1 and dotted lines in Fig. 2.

K is the printing roller mounted upon the spindle G .

K' and K^2 are side arms swung upon the spindle G .

K^3 and K^4 are spindles journaled in the arms K' and K^2 and on which are mounted the inking roller K^5 and distributing roller K^6 respectively.

It will, of course, be understood that the roller K^5 is provided with a covering of soft absorbent material such as felt designed to carry a charge of printing ink. The roller K^6 is formed of rubber and runs in contact with the inking roller K^5 and the printing roller K thereby transferring a sufficient supply of ink from the inking roller to the printing roller. Each arm K' and K^2 is provided with an open slot K^7 designed to engage and extend over the rod I when in position within the machine.

L and L' are cross rods secured in the plates B and B' .

L^2 and L^3 are downwardly spring held arms swung at their inner ends upon the rods L and L' and L^4 and L^5 are paper cutting knives secured to the outer ends of the arms L^2 and L^3 which are swung at their inner ends on the rods L and L' . The knives L^4 and L^5 are secured to the arms L^2 and L^3 in such position and the arms L^2 and L^3 swung from such center that the knives remain in the same angular position to the periphery of the paper rolls as it decreases from a maximum to a minimum diameter.

L^6 and L^7 are rods extending between the arms L^2 and arms L^3 .

L^8 are spools mounted upon the rods L^6 and L^7 and provided with serrated rims L^9 designed to engage the surface of the paper rolls.

L^{10} is a ratchet wheel secured to each of the rods L^6 and L^7 .

L^{11} is a gravity dog carried by each spool L^8 in engagement with the ratchet L^{10} .

M is an operating lever secured to the end of each rod L^6 and L^7 and provided with a weighted lever end M' . Each rod L^6 and

L⁷ is provided with a reduced portion L¹² having an annular groove L¹³ formed there-in and a further reduced squared end L¹⁴. The lever M is provided with a recess M².

5 M³ is a securing pin extending through the lever M and engaging the groove L¹³ thereby securely holding the lever in position on the reduced portion L¹² and yet capable of free rotary movement thereon.

10 O is a ratchet wheel mounted on the squared end L¹⁴, the teeth of which are set in the reverse direction to the ratchet wheel L¹⁰ hereinbefore described.

L¹⁵ is a co-acting dog carried by the lever

15 M and engaging the ratchet wheel O.

The carriage B is slidably supported upon the rollers B¹⁰ which travel in the grooves A⁶ and front rollers B¹¹ which rest upon the counter or supporting structure on

20 which the cabinet or casing A is mounted.

Having described the principal parts involved in my invention I will briefly describe the operation of the same.

In Fig. 2, it will be noticed that the printing roller K is in contact with the paper strip D³ passing over the platten roller F. By drawing on the free end of the paper strip projecting from beneath the knife L⁵ the paper roll is unwound and as the strip

30 passes over the platen roller F beneath the printing roller K an advertisement is printed thereon by means of the printing roller. The piece of paper then is torn off the

knives L⁵ serving to sever the paper. In

35 order to feed the paper forward sufficiently to provide another gripping edge projecting from beneath the knives L⁵ the lever M at the end of the arm L⁷ is raised thereby turning the roll L⁷ by means of the ratchet

40 O and dog L¹⁵. This rotary movement of the rod turns the ratchet L¹⁰ engaging the dog L¹¹ thereby turning the spool L⁸, the serrated edges of which are in contact with the paper. This serves to turn the paper

45 roll a short distance to feed the previously

cut edge forwardly of the paper cutting

knife.

If it is desired to print an advertisement on the strip of paper D² of the roll D instead of on the strip D³ of the roll D' I raise the lever J' which simultaneously raises the cam lever H and depresses the inner end of the lever J³ carrying the platen roller F³ by means of the connecting links

55 J⁵ and J². By this operation it will be seen

that the printing roller is raised slightly

by the oval cam H' so as to raise the print-

ing surface of the printing roller out of con-

60 tact with the paper strip D. Simulta-

neously the platen roller carrying the paper

strip D² is carried into engagement with

the printing roller as indicated by dotted

65 position 3 shown in Fig. 2. The paper

strip D² may then be drawn off the roll D

and printed in a similar manner as pre-

viously described in relation to the paper roll D'. As previously indicated the arms L² and L³ are swung from such center and the knives L⁴ are secured to the ends of the arms at such an angle that they will always 70 remain in the same angular relative position to the periphery of the paper roll as the paper strip is withdrawn off the roll reducing the diameter of the same from a maximum to a minimum diameter.

75 When it is necessary to change or clean the printing roller the cover A³ is swung down into the position shown by dotted lines in Fig. 2, such cover thus forming a table. The hooks K⁷ are then unhooked from the 80 rod I and the printing mechanism withdrawn through the opening A² on to the table A⁴.

85 Although I have shown one continuous printing roller it will, of course, be understood that the roller may be divided into several sections, each section carrying a different portion of advertising matter and which may be separately engaged with different colored ink rollers, there being, of 90 course, a separate inking and distributing roll for each section.

When it is necessary to place a new roll of paper in the machine all that it is necessary to do is to withdraw the supporting frame 95 B into the position shown by dotted lines in Fig. 2.

What I claim as my invention is.

1. A wrapping paper printing machine comprising upper and lower rolls from 100 which paper is drawn, printing means common to both rolls, and means actuated by the withdrawal of the paper to cause the printing action to take place on the roll from which the paper is being drawn.

105 2. A wrapping paper printing machine comprising a main frame, a plurality of rotatable paper roll supports, and a printing mechanism provided with a printing roller and means for carrying the printing roller 110 alternately into engagement with the paper of one roll and simultaneously out of engagement with the other roll.

115 3. A wrapping paper printing machine comprising upper and lower rolls of paper 120 suitably supported and from which paper is drawn, a printing roller, means whereby said roller is moved into printing contact with either of the rolls and means whereby one of said rolls may be given movement simultaneously in relation to the printing roller.

125 4. A wrapping paper printing device comprising a main frame, a plurality of rotatable paper roll supports, platen rollers over which the paper strips pass from the rolls, a printing mechanism provided with a printing roller, and means for carrying the printing roller alternately into engagement with the paper of one roll and simultaneously out 130

of engagement with the paper of the other roll, as and for the purpose specified.

5. A wrapping paper printing machine comprising a main casing, a pair of rotatable paper roll supports, an upper and lower platen roller over which the paper of each roll passes, a printing mechanism provided with a printing roller, means for lowering the printing roller into contact with

10 the paper of the lower roll and simultaneously lowering the upper platen roller and the paper thereon out of contact with the printing roller and means for raising the printing roller from contact with the paper of the lower roll, and simultaneously lowering the upper roll into contact with the printing roller, as and for the purpose specified.

6. In a wrapping paper printing machine, 20 the combination with the rotatable paper roll support and the cutting knife extending longitudinally of the paper roll, of a suitably supported shaft extending parallel with the paper roll, rotatable members supported 25 upon the shaft having a serrated periphery in engagement with the paper roll, a turning lever designed when raised to turn the rotatable members and the paper roll in contact therewith, and to fall back to its normal 30 position out of engagement with said rotatable members, as and for the purpose specified.

7. A wrapping paper printing machine comprising a main supporting frame, a pair 35 of rotatable roll supporting members supported in the frame, a pair of platen rollers, a printing roller supported on a cross shaft, cam levers supported in the frame at each end of the shaft and on the cam of which 40 the ends of the shaft rest, means for lowering the upper platen roller, and means for simultaneously turning the cams to raise the printing roller, as and for the purpose specified.

45 8. In a wrapping paper printing machine, the combination with the supporting frame having suitable slots therein, a printing roller provided with a supporting shaft having its ends extending through the aforesaid 50 slots, an oval cam resting between the end of the slot and the printing roll supporting shaft, a supporting lower platen roller, a pair of movable platen rollers, a main operating lever, and a link and lever connection

between the main operating lever and the 55 movable platen roller and main operating lever and cam roller, as and for the purpose specified.

9. A wrapping paper printing machine comprising a main supporting frame, a pair 60 of rotatable roll supporting members supported in the frame, a pair of platen rollers, a suitably supported printing roller interposed between the platen rollers, cam levers supported in the frame at each end of the 65 shaft and on the cam of which the ends of the shaft rest, as and for the purpose specified.

10. In a device of the class described, a supporting structure having slotted side 70 walls, an upper platen roller and a lower platen roller supported between such wall, a printing roller interposed between the platen rollers, a supporting shaft extending through the slots of the side walls and on 75 which the printing roller is supported, a cam means located in each slot for raising the shaft and the printing roller out of contact with the lower platen roller, as and for the purpose specified.

80 11. In a wrapping paper printing machine, the combination with a paper roll and rotatable support therefor, of a cutting blade, swinging arms supporting the blade, a shaft carried by the arms, a lever swung 85 on the shaft, a serrated drum mounted and normally in engagement with the paper roll and means whereby the lever and shaft and the shaft and drum are engaged during the upward throw of the lever and disengaged 90 during the downward throw of the lever, as and for the purpose specified.

12. In a wrapping paper printing machine, the combination with the casing having an opening therein, an upper platen 95 roller and a lower platen roller over which separate strips of paper are designed to pass, a printing roller removably supported within the casing in proximity to said opening and means for carrying the printing 100 roller and paper passing over the upper and lower platen rollers alternately in and out of engagement, as and for the purpose specified.
